Patented Dec. 7, 1926.

UNITED STATES PATENT OFFICE.

ALBERT C. BELLES, OF BEAVER FALLS, PENNSYLVANIA, ASSIGNOR TO STANDARD GAUGE STEEL COMPANY, OF BEAVER FALLS, PENNSYLVANIA, A CORPORATION OF PENNSYLVANIA.

WIRE STRAIGHTENER.

Application filed June 8, 1925. Serial No. 35,757.

This invention relates to wire straightening mechanism, and particularly to a device intended for operating on wires of different gages and effective to straighten wire that has been run therethrough, the said invention having novel adjustable means which may be expeditiously manipulated to adapt it for operating on wire of different gages.

It is a further object of this invention to produce a rotatable member having elements mounted therein which constitute what may be termed dies or guides which tend to straighten wire, and the said dies or guides are adjustable from the exterior of the device so that they can be expeditiously manipulated.

It is a still further object of this invention to produce a mechanically operated means for moving one or more of the dies radially, the said device being effective to force the die inwardly or to release it in order that the said die under centrifugal force may move outwardly.

The invention may be regarded as an improvement on a wire straightening arbor forming the subject-matter of Patent No. 1,473,256, dated November 6th, 1923, to E. F. Shuster, as it affords a means for moving one or more of the dies similar to those of the aforesaid patent while the device is rotating so that if unusual conditions of the wire being treated warrant it, the die may be forced closer to a coacting element or it may be released so that it will move outwardly under the influence of the centrifugal force.

It is a still further object of this invention to produce a wire straightener having a rotatable element or arbor and a collar slidably thereon, the said rotatable element having a lateral slidable wire engaging device or die pressed inwardly by movement of the collar which may be regulated to increase or reduce the pressure of the element or die against the wire to be straightened, as occasion demands, the same being operative, as stated, while the arbor is in operation or rotation.

With the foregoing and other objects in view, the invention consists in the details of construction, and in the arrangement and combination of parts to be hereinafter more fully set forth and claimed.

In describing the invention in detail, refer-

ence will be had to the accompanying drawings forming part of this application wherein like characters denote corresponding parts in the several views, and in which—

Figure 1 illustrates a view in side elevation of a wire straightener embodying the invention;

Figure 2 illustrates a sectional view on the line 2—2 of Fig. 1; and

Figure 3 illustrates an underneath plan view of a fragment of the said device.

In these drawings, 5 denotes bearings in which trunnions 6 of a rotatable die holder 7, hereinafter referred to as an "arbor", are rotatable, and the said arbor may be turned or driven in any suitable manner, as through a pulley 8. The arbor is cylindrical and is provided with transversely disposed apertures, said apertures having a bore 10 at one end which is of greater diameter than the bore 11 at the opposite end. Each aperture has a die 12 threaded in it, and as shown in the drawing, the die occupies that portion of the aperture having the small diameter, but its head 13 is located at the step between the small and large bores of the arbor.

An intermediate die 14 and parts thereof are slidable in the large bore of the arbor and is adapted to coact with the die 12. The die 14 has a die carrier 15 and the die carrier has a stud 16 whose head bears against a camming surface 17 of a sliding ring or collar 18, it being understood that the ring 18 is slidable longitudinally of the die carrier for the purpose of operating on the die carrier 15.

Keys 19 and 20 serve to couple the arbor to the ring or collar so that the ring or collar rotates with the arbor but may slide axially thereof. The collar 18 has a tongue and groove joint with a split ring 21, the sections of which may be provided with apertured lugs 22, and the lugs may be secured together by fastenings 23 such as bolts or the like. The collar is rotatable in the split ring and the said ring has lugs or projections 24 and 25 extending from its side which enter apertures in the arms of a yoke 26. The yoke has a crank lever 27 associated with it, which is pivoted at its angle on a pintle or bolt 28 supported by a bracket 29, which bracket is stationary with relation to the arbor. The arms of the yoke have slots 30 in which the lugs project, and the arrangement is

such that sufficient clearance is afforded for the operation of the device as the lever oscillates.

- From an inspection of the drawings, and 5 from the foregoing description, it will be apparent that the oscillation of the lever will move the collar axially of the arbor and that the camming surface of the collar will operate to force the intermediate die inwardly, as shown in the drawings, whereas 10 if the lever is manipulated to carry the collar so that the camming surface is out of engagement with the stud 16, the die will be free to move outwardly by reason of 15 centrifugal force, and by this means, the operation of the lever will force the die inwardly or release it in order that the die will operate satisfactorily on wire having 20 different conditions.
- While in practice the manual control of one of the dies in the manner stated has been found satisfactory, it will be apparent 25 that the arrangement could be extended to operate in conjunction with other dies, and the inventor does not wish to be limited with respect to this detail of construction.

I claim:

1. In a wire straightener, an arbor having a plurality of laterally adjustable dies, a 30 collar splined on the arbor, means for moving the collar axially of the arbor while the collar is rotating, and means associated with the collar and with an intermediate one of said dies whereby the aforesaid movement of the collar imparts motion to the die to force it inwardly, the said die being returned by centrifugal force when the said collar is moved in another direction.
2. In a wire straightener, an arbor having 35 a plurality of dies adjustable laterally of the said arbor, one of the said dies having lateral sliding motion with respect to another die, a collar splined on the arbor and rotatable therewith, means for moving the collar axially of the arbor while rotating, and means associated with the collar and the die for forcing the die inwardly and for permitting it to move outwardly under 45 centrifugal force.
3. In a wire straightener, an arbor having a plurality of laterally adjustable dies, one of which is slidable, a collar splined on the arbor and rotatable therewith, means for moving the collar axially of the arbor while 50 rotating, the said collar having a slot, a wall of which constitutes a camming surface, and a member engaged by the camming surface

effective to impart motion to the sliding die for moving the die inwardly as and for the purpose described.

60 4. A wire straightener comprising a rotatable die carrying body, a plurality of dies carried thereby between which the wire to be straightened is passed, an intermediately located two-part die, one part of the said two-part die being movable toward its opposite part and to wire engaging position, and a manually operated slidable member mounted upon the rotatable die carrier.

65 5. A wire straightener comprising a rotatable body or shaft having a longitudinal opening therethrough, a plurality of transverse openings for the reception of dies, dies maintained within the openings and an intermediate opening for the reception of 70 an intermediate two-part die having a fixed member and a slidable member, a longitudinally movable die engaging means slidable upon the exterior of the rotatable body for engagement with a part of the intermediate 75 die to move the same to operative position.

6. A wire straightener comprising a rotatable arbor or shaft having therethrough a longitudinal passage for wire and transverse bores, an intermediate transverse bore having 80 portions of different diameters, dies carried by the bores, an intermediate die carried by the intermediate bore, said die comprising a fixed member and a slidable member which is movable to and from the fixed member of the die, a slidable member maintained in rotative engagement with the shaft and constructed to engage the slidable member of the die, and manually controlled means for moving the second-mentioned 85 slidable member.

7. A wire straightener comprising a rotatable shaft provided centrally with a longitudinal aperture for the passage therethrough of a wire to be straightened, a 100 plurality of transverse apertures for straightening dies, one of said apertures being located mid way between the other apertures for the reception of a two-part die, a two-part die one part thereof being 105 movable to and from its other part, a slid- able member mounted upon the exterior of the shaft and rotatable therewith, said mem- ber having an inclined portion for engage- ment with the movable member of the die, 110 and manually actuated means for recipro- cating the slide to effect an inward move- ment of the movable part of the die.

ALBERT C. BELLES.
